WILLIAM WALLACE McCALL, OF KANSAS CITY, MISSOURI

SPINNING TOP

Application filed October 2, 1930. Serial No. 485,920.

My invention relates to improvements in spinning tops.

It relates particularly to a type of top, such as is illustrated and described in an application filed by me August 20, 1930, Serial Number 476,513, and to mechanism for spinning the same.

The top referred to is spun by being removably mounted on a suitable support on which it is first rapidly revolved by mechanism provided for the purpose, after which it is released from the support and permitted to spin on the floor or other suitable even surface.

My present invention relates particularly to a novel mechanism for spinning the top on its initial support, said mechanism providing novel means by which the top is securely held on its initial support, revolved thereon, and then automatically released from the holding mechanism and permitted to release itself from said initial support.

My invention provides further a top, of general ellipsoidal shape, having novel means by which it is first revolved around its minor axis on a suitable support on which it is releasably held until the initial revolving operation has been effected, after which it is automatically released from the holding means, and permitted to spin freely on an even surface, upon which it will assume a position in which its major axis will be vertical.

My invention provides further a novel top spinning mechanism which is simple, cheap, durable, strong, not likely to get out of order, and which will impart a high speed of revolution to the top.

The novel features of my invention are hereinafter fully described and claimed.

In the accompanying drawings, which illustrates the preferred embodiment of my invention,

Fig. 1 is a central vertical sectional view of my improved top and spinning mechanism.

Fig. 2 is a side elevation of the same with the parts in operative positions.

Fig. 3 is a side elevation of the top, spindle and spool, the top being shown released

from the propelling member and the latter and spool being released from the top string.

Fig. 4 is a side elevation of the top, spindle and spool, the top being shown still engaged with the propelling member, and the latter and the spool being released from the top string.

Fig. 5 is a section on the line 5—5 of Fig. 2.

Fig. 6 is a side elevation of my improved top shown in the spinning position in which its major axis is vertical.

Fig. 7 is a side elevation of the propelling member removed from the spool.

Similar characters of reference designate similar parts in the different views.

1 designates the body of the top, which is ellipsoidal in shape, being longer than wide with rounded spinning ends and convex between its ends.

A—B designates the major axis of the top, and C—D the minor axis thereof.

The top 1, which has the shape of a prolate spheroid, if spun rapidly around its minor axis C—D, with the latter vertically disposed, will almost at once assume a position at right angles to its original position, as shown in Fig. 6, in which the major axis is vertical and the minor axis horizontal.

Such twirling of the top around its minor axis may be effected with the fingers of the operator, but the top will spin much longer, when similarly rotated by the spinning mechanism illustrated in the drawings.

In the spinning mechanism illustrated in the drawings, there is provided a spindle comprising a rod 2 having at its upper end a handle 3. The spindle 2 is adapted to be releasably inserted in a hole 4 in the top 1, such hole being coincident with the minor axis C—D of the top.

For initially revolving the top 1 on the spindle 2, there is revoluble on the spindle 2, just below the handle 3, a spool 5. For limiting the downward movement of the spool 5 on the spindle 2, there is mounted on the spindle 2 just below the spool 5 a fixed collar 6.

To revolve the top 1 when the spool 5 is revolved, the spool has mounted on it a resilient propelling member, which, as shown, comprises a spring wire 7, which extends lon-

gitudinally through a longitudinal peripheral groove 8 in the spool 5. The upper end of the spring wire or propelling member 7 is extended over the top of the spool 5, and has its upper end downwardly turned and extended into a hole provided therefor in the top of the spool.

In its free condition, the spring wire 7 extends downwardly and outwardly below the lower end of the spool 5, the lower end of the wire 7 having a hook or inwardly turned portion 9, which is adapted to enter a peripheral hole 10 in the top 1 at one side of and adjacent to and inclining toward the spindle receiving hole 4, Fig. 1. Normally the propelling wire 7 will assume the position shown in Fig. 3, in which the hook 9 is out of engagement with the top 1. The wire 7, however, is adapted to be engaged by a flexible member, such as a top string 11, when the latter is wound around the spool 5, to be pressed toward the spool 5 and to a position in which the hook 9 will enter the inclined hole 10, Fig. 1, thus releasably lockingly holding the top 1 from sliding off the spindle 2, and serving to revolve the top, when the string 11 is pulled off the spool 5 to revolve the latter.

In spinning the top, the top string 11 has one end inserted in the upper part of the groove 8, and then wound around the spool 5, as shown in Figs. 1 and 2. The winding of the string 11 on the spool 5 will press inwardly the free end of the spring wire 7 to its operative position, shown in Figs. 1 and 2. The top 1 is then slipped on the spindle 2 to a position in which the hook 9 will enter the inclined hole 10, Figs. 1 and 2. The top will be held by the hook 9 from slipping from the spindle 2.

Then the string 11 is pulled rapidly from the spool 5, thus rapidly revolving the spool 5 and, through the spring wire 7, the top 1 on the spindle 2. When the string 11 has been pulled clear of the spool 5, the spring wire 7 will spring automatically, by reason of its tension, to the position shown in Fig. 3, in which position the hook 9 will pass out of the inclined hole 10. The top 1 being thus freed from the spring wire 7 will slip from the spindle 2, and for a short time will revolve on the floor or other even surface with its major axis horizontal.

The rapid revolving of the top 1 will cause it to assume the position shown in Fig. 6, in which position, its major axis A—B will be vertical and its minor axis C—D horizontal. The top will then spin in this last named position until it stops.

By providing the automatically releasing spring wire 7 to hold the top while the string 11 is wound, the operator does not need to hold the top on the spindle 2, and the top may be carried in the pocket engaged operatively

with the spindle 2 and spring wire 7 without the string 11 unwinding.

As shown in Fig. 1, the hole 10 may have fitted in it a metal bushing 12, to minimize wear of the top by the spring wire 7. 70

By having the spindle 2 projecting, as shown, below the bottom of the top 1, the spindle may be pressed at its lower end firmly against the surface on which the top is to be spun without such pressure being transmitted to the top. When the spindle is so held, the top can be spun, without its describing a large circle, in a relatively small area. By having the resilient wire 7 hold the top spaced from the lower end of the spindle 2, 80 the top will be held from resting on the floor.

It will be noted that the top is revoluble on the spindle without longitudinal movement in any plane transverse to the spindle for the full range of movement of the top 85 lengthwise of the spindle, and is revoluble for such full range of movement independently of the spindle.

I do not limit my invention to the structure shown and described, as modifications, within the scope of the appended claims, may be made without departing from the spirit of my invention. 90

What I claim is:—

1. In a spinning top, a spindle, a top revoluble thereon and removable therefrom at one end thereof, a spool revoluble on said spindle, a propelling member carried by said spool and normally disengaged from said top and movable into driving engagement therewith, and in such driving engagement holding said top on said spindle, and a flexible member adapted to be wound on said spool for revolving the latter, and when so wound engaging and forcing said propelling member into driving and holding engagement with said top. 95

2. In a spinning top, a spindle, a top revoluble thereon and removable therefrom at one end thereof, a spool revoluble on said spindle, a resilient propelling member carried by said spool and normally disengaged from said top and movable into driving engagement therewith and in such engagement holding said top on said spindle, and a flexible member adapted to be wound on said spool for revolving the latter and when so wound engaging and pressing said propelling member into driving and holding engagement with said top. 110

3. A top having a spindle receiving hole and provided with a peripheral hole inclined to the first named hole, a spindle releasably insertible in said spindle receiving hole, a spool revoluble on said spindle, a resilient propelling member carried by said spool and normally disengaged from said top and movable into said inclined hole and when in said inclined hole holding said top from moving off from said spindle, and when revolved 125 130

with said spool and so engaged with said top revolving the latter, and a top string adapted to be wound on said spool for revolving the spool and when so wound forcing said propelling member into and holding it in said inclined hole.

4. A top having a spindle receiving hole and a peripheral hole inclined thereto, a spindle releasably insertible into said spindle receiving hole, a spool revoluble on said spindle and adapted to have wound thereon a top string for so revolving said spool, and a resilient propelling member carried by said spool and having a hooked end normally disengaged from said top but movable into a position in which said hooked end will enter said inclined hole and hold the top on said spindle, said resilient member being adapted to be pressed into the engaging position by said top string, when the latter is wound in operative position on said spool.

5. A top longer than wide having rounded spinning ends and convex between its ends, a support on which the top is releasably revoluble around its minor axis, a spool revoluble on said support and adapted to be engaged and revolved by a top string wound thereon, and a propelling member carried by said spool and adapted to be engaged and moved by said top string, when the latter is wound on said spool, so as to releasably engage said top at one side of the minor axis thereof, and arranged, when so engaged, to hold and revolve said top on said support, and when disengaged from said string disengaging from said top.

6. A top longer than wide having rounded spinning ends and convex between its ends, a support on which the top is releasably revoluble around its minor axis, a spool revoluble on said support and adapted to be engaged and revolved by a top string adapted to be wound thereon, and a resilient propelling member carried by said spool, and by its resiliency being held normally disengaged from said top, but adapted to be engaged and pressed by said top string, when the latter is wound on said spool, into engagement with said top at one side of the minor axis thereof, and having means, when so engaged with said top, for holding the latter and revolving it on said support.

7. A top longer than wide having rounded spinning ends and convex between its ends and having a spindle receiving hole coinciding with its minor axis and having a peripheral hole at one side of and inclined toward said spindle receiving hole, a spindle releasably insertible into said spindle receiving hole, a spool revoluble on said spindle and adapted to have a top string wound thereon for revolving said spool on said spindle, and a resilient propelling member carried by said spool and having a hooked end adapted to enter said inclined hole for hold-

ing the top and revolving it on said spindle, and normally movable from engagement with said top but adapted to be pressed into engaging position with the top by said top string, when the latter is wound on said spool. 70

8. In a spinning top, a top having a hole therethrough, a spindle adapted to be extended through said hole and to project at its lower end from the bottom of said top, said top being revoluble on said spindle and 75 slideable therefrom off said projecting end, and means for releasably holding said top on said spindle spaced from said lower end and for revolving said top on and permitting it to so slide from said spindle after such 80 revolution has been effected.

9. In a spinning top, a support on which said top is revoluble and releasable therefrom, said support being adapted, when supporting said top to project at its lower end below the bottom of said top, and means for 85 releasably holding said top on said support spaced from said lower end thereof and for revolving said top on and permitting it to be released therefrom after such revolution 90 has been effected.

10. An ellipsoidal top having a hole aligned with its minor axis and extending entirely through said top, a support having a spindle removably insertible through said hole and 95 adapted to have its lower end projecting below the bottom of said top, said top being revoluble without longitudinal movement on said spindle in a plane transverse to said spindle for the full range of movement of 100 said top lengthwise of said spindle, and means for revolving said top on said spindle.

In testimony whereof I have signed my name to this specification.
